DESIGN FOR A MATTRESS BORDER

Application filed March 23, 1931. Serial No. 39,217. Term of patent 14 years.

To all whom it may concern:

Be it known that I, HUGO PERLESZ, a citizen of the United States, residing at Chicago, in the county of Cook and State of Illinois, have invented a new, original, and ornamental Design for Mattress Borders, of which the following is a specification, reference being had to the accompanying drawings, forming part thereof.

Figure 1 is a plan view of a fragment of a mattress border showing my new and original design, and

Fig. 2 is a detail sectional view taken on line 2—2 of Fig. 1.

The dominant feature of the ornamental design resides in the oarlock-like elements arranged in rows symmetrical with respect to a longitudinal median line and in staggered relation.

I claim:

The ornamental design for a mattress border, as shown and described.

HUGO PERLESZ.
